CLAIM

The ornamental design for a combined container and bins, as shown and described.

DESCRIPTION

FIG. 1 is a perspective view of a combined container and bins showing my new design;

FIG. 2 is a front perspective view of a bin, shown separately for clarity of illustration;

FIG. 3 is a front perspective view of a bin cover, shown separately for clarity of illustration;

FIG. 4 is a perspective view of a container, shown separately for clarity of illustration;

FIG. 5 is a top plan view of FIG. 4;

FIG. 6 is a side elevational view of FIG. 4, all sides being identical;

FIG. 7 is a bottom plan view of FIG. 4;

FIG. 8 is a top plan view of FIG. 2;

FIG. 9 is a side elevational view of FIG. 2, the opposite side being a mirror image;

FIG. 10 is a bottom view of FIG. 2;

FIG. 11 is a rear perspective view of FIG. 2;

FIG. 12 is a side elevational view of FIG. 3;

FIG. 13 is a front elevational view of FIG. 3;

FIG. 14 is a bottom plan view of FIG. 3; and,

FIG. 15 is a top plan view of FIG. 3.
